CLAIM

The ornamental design for a wine gift tag, as shown and described.

DESCRIPTION

FIG. 1 is a perspective view of a wine gift tag, showing my new design;

FIG. 2 is a front elevational view of the invention;

FIG. 3 is a rear elevational view of the invention;

FIG. 4 is a left-side elevational view of the invention, the right-side elevational view being a mirror image thereof; and,

FIG. 5 is a top plan view of the invention, the bottom view being a mirror image thereof.

1 Claim, 1 Drawing Sheet
